(57) **CLAIM**

The ornamental design for an underwater camera, as shown and described.

DESCRIPTION

FIG. 1 is a front perspective view of an underwater camera, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a left front perspective view thereof shown in a state of use;

FIG. 10 is a right front perspective view thereof shown in a state of use; and,

FIG. 11 is a left front perspective view thereof shown in a state of use.

The broken lines in the drawings illustrate portions of the underwater camera or unclaimed environment and form no part of the claimed design.

1 Claim, 11 Drawing Sheets
